UNITED STATES PATENT OFFICE

MICHEL MODO, OF LUXEMBURG-VILLE, LUXEMBURG

AUTOMOBILE DOOR LATCH

Application filed May 31, 1927, Serial No. 195,546.

The present invention relates to latches and has more particular reference to latches used on automobile doors or for like purposes.

A primary object of the invention is to provide a latch utilizable on automobile doors and adapted to ensure a very reliable fastening of such doors even in the case of prolonged vibrations of the door as for example when the automobile travels on a bumpy road for a long time.

A further object of the invention is to provide a latch utilizable on automobile doors and having such an improved structure as to automatically bring a door of that type to its securely fastened position under the repeated vibrations of said door should the latter happen to have been only partly closed.

A still further object of the invention is to provide a latch utilizable on automobile doors and having such an improved structure as to automatically take up any play of the door in the long run.

A still further object of the invention is to provide a latch utilizable on automobile doors and so structured as to securely hold a door of that type in three directions, to wit: sidewise, lengthwise and heightwise.

A still further object of the invention is to provide a latch utilizable on automobile doors and adapted to relieve the doors of that type of the greater part of their wear and tear while preventing any rattling thereof.

A still further object of the invention is to provide a latch utilizable on automobile doors and so constructed as to leave a clearance around such doors whereby many disadvantages, such for instance as jamming effects due to the expansion of wood of which the doors are usually made, are avoided.

With these and such other objects in view as will incidentally appear hereafter, the invention comprises the novel construction, combination and arrangement of parts that will now be fully described with reference to the accompanying drawing forming a part of same and wherein:—

Fig. 1 is a front elevation of a latch constructed in accordance with my invention.

Fig. 2 is an end elevation of the same.

Fig. 3 is an elevation of the opposite end of the latch from that shown in Fig. 2.

Fig. 4 is a sectional transverse view of the same on the plane indicated by the line 4—4 of Fig. 1.

Fig. 5 is a plan of the same with the lever L shown in section.

Fig. 6 is an elevation of the latch, partly in section, and with the casing plate removed, and showing the latch in closed position.

Fig. 7 is a similar view with the keeper removed, showing the parts in released position.

Fig. 8 is a horizontal sectional view of the plane indicated by line 8—8 of Fig. 6.

Fig. 9 is a similar view on the plane indicated by the line 9—9 of Fig. 7.

Fig. 10 is a similar view of the plane indicated by line 10—10 of Fig. 7.

Like reference characters designate like parts throughout the several views.

In said figures, A is the bolt or peculiar shape, B is the latch case, C, C are screws forming adjustable pivots on which the bolt A is rotatably mounted. Only the top part of the pivots are threaded. In the top of the bolt A the pivot engages into a recess which contains a spring S which is active to bring back the bolt A to its open position. D is a detent for firmly holding in opened position an L-shaped wedge G having a tapering vertical leg and adapted to maintain the bolt A in closed position. Said wedge has a horizontal arm g, provided with an arcuate slot g'. H is a lever used for lifting the wedge G; K is a co-operating lever provided with a square opening K for the stem of an outer knob (not shown) of the door, L is a lever which in practice is actuated by an inner knob of the door, and M is the keeper into which the bolt A is adapted to engage.

The operation of the latch is as follows:

In the closed position the bolt A is engaged in its recess r, and cannot move in the opening direction, because of the engagement of the conical wedge G between the heel e of the bolt and the lock case B.

In order to disengage the heel e, the wedge G has to be lifted above the heel, so as to

allow this latter to turn freely underneath the wedge.

The lifting of the wedge G which sets free the heel e may be accomplished either by the side lever K or the upper lever L (see Fig. 3). By turning one of these two levers the central lever I enters into a balancing movement, which determines an ascending movement of the stud z, which by sliding in the slot g', raises the wedge G leaning on N (Fig. 3) against the latch case and guided on the other hand through a vertical groove y by means of a heel O'.

The wedge G is now in its top or lifted position. By pushing or pulling the door a little, in order to open it, a slight clearance is left on the lateral side of the door, so that the detent D is freed a little and the small heel o'' of its rod (which is moved forward by a spring P) engages into a recess at the bottom of the wedge G and prevents this latter from sliding down while the knob which operates the part K is brought back in its previous position by the pull-back spring p (Fig. 7). By opening the door the bolt A rotates slightly round its pivots C, actuated also by the spring S which brings back to its extreme open position the bolt A and so removes the heel e underneath the wedge G.

This latter comes so to stand with its little tongue o on the heel e, when the bolt A is in its largest open angular position.

Owing to this spring S, the following incident is prevented: The door being open, the latch D might be incidentally pushed inside so that the wedge G would by this fact be freed and slide down between the heel and the latch case B and so wedge up the heel e and thus prevent the closing of the door. However this case does not occur, because the wedge, even if not supported by the detent D, rests on the heel and is sustained in this position of the open bolt by means of the spring S.

The detent D maintains the wedge G in its raised position in the case where the door is open and the bolt might have been incidentally turned in the closing direction (in which case the heel e would no longer support the wedge).

By pushing the door in the closing direction (Fig. 9) the guide f bends over x and makes the bolt A turn towards its recess r. The heel e passes underneath the wedge G (Fig. 2). The detent D, which supports the wedge G by its small heel o'', (Fig. 9), in raised position, abuts against the wall of the keeper M while the door is being closed. Being in this way pushed backwards the heel o'' no longer retains the wedge. Before the door is completely closed, being ajar by 12 mm., the wedge G does not rest on the heel e, but pushed by the spring t (Fig. 7) it falls down, guided by its heel o' (Fig. 6) along a suitable groove y (Fig. 3). The

wedge being in this manner located between the heel e of the bolt A and the latch case B prevents the heel e from rotating in its recess and by this fact the bolt A is firmly wedged in its closed position.

As soon as the wedge comes to stand behind the heel e, it begins to fall down, but not immediately down to the bottom, because the door is not completely closed. However the door cannot open now, for as the wedge is conical, with its sharp end turned downwards, the slightest jolting of the car in movement causes it to continue to fall, so that it gradually pushes back the heel e in the closing direction until the bolt A is completely engaged.

It will be appreciated that numerous minor constructional details of the latch might be altered without departing from the scope of the invention as set forth in the appended claims.

What I claim is:—

1. A latch for automobile and like doors comprising in combination a case, a pair of adjustable pins supported by the case, a keeper, a bolt pivotally carried by the pins and having a heel portion on one side of its pivoting axis and keeper-engaging portions on the opposite side, a movable wedge adapted to engage said bolt and hold it in closed position, a detent for retaining the wedge in open position, spring means for pulling back the bolt, and inner and outer levers for transmitting the knob impulses to the wedge.

2. A latch for automobile and like doors comprising in combination a case fixed to the door, a pair of adjustable pins supported by the case, a bolt pivotally carried by the pins and having a tapering heel portion on one side of its pivoting axis and a pair of keeper-engaging portions on the opposite side, an L-shaped wedge movable in the case and having a vertical tapering leg for engaging the heel of the bolt, a detent for holding the wedge in open position, spring means for pulling back the bolt, inner and outer operated levers for transmitting the knob impulses to the wedge, and a keeper fixed to the automobile body adjacent the lock case and having bolt-engageable members.

3. A latch for automobile and like doors comprising in combination a case fixed to the door, a keeper fixed to the automobile body and having a curved bolt-engaging abutment, a pair of adjustable pivot pins supported by the case, a bolt pivotally carried by the pins and having a tapering heel on the rear side of its pivoting axis and two keeper-engaging lug portions on the opposite side, one of said lug portions being curved for engaging the abutment of the keeper, an L-shaped wedge movable in the lock case and having a vertical tapering leg for engaging the bolt heel and holding the bolt against rotation in closed position and a tongue on

its horizontal leg, a detent engaging the wedge tongue for retaining the wedge in open position, spring means for pulling back the bolt, and inner and outer operated levers for transmitting actuating impulses to the wedge.

4. A latch for automobile and like doors comprising in combination a case fixed to the door, a keeper fixed to the adjacent part of the automobile body and having a flaring recess and an abutment engageable by the bolt and a shoulder also engageable by another part of the bolt, a pair of adjustable pins supported by the case, a bolt pivotally carried on both sides by the pins and having a tapering heel on the rear side of its pivoting axis and two keeper-engaging lug portions on the opposite side, one of said lug portions being curved towards the other for engaging the abutment of the keeper whereas the other one having a flange for engaging the keeper shoulder, an L-shaped wedge movable in the case and having a vertical tapering leg for engaging the bolt heel and holding the bolt against rotation in closed position and a tongue on its horizontal leg, a detent engaging the wedge tongue for retaining the wedge in open position, spring means for pulling back the bolt, and inner and outer actuated levers for transmitting the actuating impulses to the wedge.
